UNITED STATES PATENT OFFICE.

ALBERT F. THAYER, OF MAPLE HILL, KANSAS.

SPRINKLING OR SPRAYING PIPE.

SPECIFICATION forming part of Letters Patent No. 388,930, dated September 4, 1888.

Application filed July 2, 1888. Serial No. 278,778. (No model.)

To all whom it may concern:

Be it known that I, ALBERT F. THAYER, of Maple Hill, in the county of Wabaunsee, in the State of Kansas, have invented a new and useful Improvement in Sprinkling or Spraying Pipes, of which the following is a specification.

This invention consists of a pipe or tube provided with a longitudinal indentation or groove, the opposite sides of which are supplied with opposite series of perforations, through which water or other liquid substance is forced and by this means converted into spray. It is useful in sprinkling flowers, gardens, lawns, washing windows, urinals, &c., and for various purposes where saturation by means of sprinkling or spraying is desired or the supply of water or other liquid in the form of spray is advantageous.

In the accompanying drawings, in which similar letters of reference indicate like parts, Figure 1 is a view in perspective of a pipe or tube embodying my invention, such as would be applicable to the end of a garden-hose, for example. Fig. 2 is a transverse section of the same. Fig. 3 is a transverse section of a pipe which is rectangular in section. Fig. 4 is a transverse section of a round pipe with an indentation or groove of curved shape.

In Figs. 1 and 2, A represents a long pipe adapted at A' to be screwed to a hose, B, or other means of connection with the source of supply of water or other liquid. The outer end, A'', is closed. a is a longitudinal V-shaped groove or indentation in whose opposite sides are made perforations a', each of which is exactly opposite a perforation on the opposite side of the groove. As the water is forced into the pipe, it rushes out through the perforations a', and the jets from each pair meet and are converted into fine spray projecting a considerable distance from the pipe, the length of

the spray-jets depending upon the head of water in the tube.

The shape of the pipe is not essential, a rectangular one, as shown in Fig. 3, being equally efficient. The groove or indentation may be other than V-shaped, a curved groove being shown in Fig. 4; but its sides at the points of the perforations must be such as to cause the opposite jets to impinge against and mingle with each other in order to form the desired spray.

I am aware that atomizers employ means—such as small nozzles placed at proper angles with each other—for converting liquids into fine spray. I do not claim, therefore, anything which is covered by such devices.

My device is a long tube having opposite series of perforations in a longitudinal indentation or groove, through which the liquid is forced and a large spray-cloud produced. I propose to use any desired liquid and to apply the invention to any stationary or movable device where the result produced will be of service.

Having thus fully described my invention, what I claim, and desire to secure by Letters Patent, is—

The herein-described sprinkling or spraying device, consisting, essentially, of a pipe or tube provided with an indentation or groove whose opposite sides are each provided with a series of perforations, each perforation in one series being opposite a corresponding perforation in the other series, whereby the jets of water issuing from each pair of perforations impinge against and mingle with each other, substantially as and for the purpose set forth.

ALBERT F. THAYER.
